DESIGN.

B. LIPPER.

DRESS OR UPHOLSTERY TRIMMING.

No. 20,054.

Patented July 22, 1890.

UNITED STATES PATENT OFFICE.

BENJAMIN LIPPER, OF PHILADELPHIA, PENNSYLVANIA, ASSIGNOR TO AUGUSTUS A. LAZARUS, ISAAC A. SCHWARZ, AND BENJAMIN LIPPER, ALL OF SAME PLACE.

DESIGN FOR DRESS OR UPHOLSTERY TRIMMING.

SPECIFICATION forming part of Design No. 20,054, dated July 22, 1890.

Application filed June 28, 1890. Serial No. 357,159. Term of patent 3½ years.

To all whom it may concern:

Be it known that I, BENJAMIN LIPPER, a citizen of the United States, and a resident of Philadelphia, Pennsylvania, have invented or 5 produced a new and original Design for Dress-Trimming, of which the following is a specification.

My design for dress or upholstery trimming is shown in the accompanying photo- 10 graphic illustration, which represents a front view of the trimming.

The design consists of a gimp background, on which is a central band composed of 15 looped threads, forming ornamentation of the character technically known as "moss" pat-

tern. The opposite longitudinal side bands of the gimp are exposed beyond this central band, and the cords of the gimp form loops extending beyond these bands, as shown.

I claim—

The design for dress or upholstery trimming, substantially as described, and shown in the accompanying drawing.

In testimony whereof I have signed my name to this specification in the presence of 25 two subscribing witnesses.

BENJAMIN LIPPER.

Witnesses:

EUGENE ELTERICH,
HARRY SMITH.
